CLAIM

The ornamental design for a wireless control module, as shown and described.

DESCRIPTION

FIG. 1 is a front perspective view of a wireless control module showing our new design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is top view thereof;

FIG. 8 is bottom view thereof;

FIG. 9 is another perspective view thereof, shown within its environment; and,

FIG. 10 is another perspective view thereof, shown within its environment.

The broken lines in the drawings depict environmental subject matter only and form no part of the claimed design.

1 Claim, 9 Drawing Sheets

US D794,577 S
